UNITED STATES PATENT OFFICE.

DAVID A. NICOSIA, OF FOREST PARK, AND HARRY SIPPEL, OF CHICAGO, ILLINOIS.

RADIOCOIL.

Application filed November 19, 1923. Serial No. 675,562.

This invention relates to a variable impedance means and particularly to a device which is adapted to be used in an electric circuit comprising a part of apparatus used in radio telegraphy or telephony.

In adjusting such a circuit to proper operating relations for varying conditions of transmission and reception, it is necessary to vary the impedance of the circuit by changing both the capacity and inductance or either thereof. Such conditions make it desirable that readily adjustable apparatus be provided and practical considerations require that such apparatus be compact, accurate, durable and capable of economical manufacture.

It is an object therefore of this invention to provide an apparatus of the class described which is compact and wherein the desired results are attained with a minimum number of soldered connections.

It is a further object of this invention to provide a device of the class described wherein a separate connection may be made with each turn of the inductance coil without the necessity of separate connections thereto for such purpose.

It is also an important object of this invention to provide a device of the class described wherein proper insulation may be provided at a minimum expense and wherein a variable connection may be made directly with each turn of an inductance coil.

Other and further important objects of this invention will be apparent from the disclosures in the specification and the accompanying drawings.

The invention in a preferred form is shown on the drawings and hereinafter more fully described.

On the drawings:

Figure 1 is a perspective view of a coil embodying the principles of the present invention.

Figure 2 is a fragmentary perspective view showing the right-hand end of the coil illustrated in Figure 1.

Figure 3 is a perspective view showing a slightly modified form of coil embodying the principles of this invention.

Figure 4 is a perspective view showing another modification.

Figure 5 is a fragmentary perspective view illustrating a portion of the form of coil shown in Figure 4.

Figure 6 is a perspective view illustrating

the use of a double contacting member in use with the form of coil illustrated in Figure 4.

Figure 7 is a fragmentary perspective view of the right-hand end of the coil shown in Figure 4.

Figure 8 is a fragmentary perspective view illustrating a modification embodying a variable condenser.

Figure 9 is a perspective view illustrating a variometer type coil.

Figure 10 is a perspective view showing the right-hand end of the coil illustrated in Figure 9.

Figures 11 and 12 are perspective views illustrating an induction coil having a modified arrangement of contacting members.

As shown on the drawings:

The reference numeral 1 indicates a suitable base formed of wood, vulcanite or any other suitable material which is preferably non-conducting. Secured to the base 1 and extending upwardly from either end thereof are uprights 2 which are constructed of suitable insulating material, such as wood, and which act to support an insulating cylinder 3 of cardboard, fibre or other suitable material in a desired position on the base 1.

The cylinder as supported on the uprights 2 is substantially parallel to the base 1 and, as shown in the drawings, the ends thereof are open.

A coil of electrical conductor comprising usual insulated metallic wire is wound on the cylinder 3 and it will be noted from an examination of the drawings this coil is so wound on the cylinder that the turns thereof extend longitudinally and parallel to the axis of the cylinder, the ends of the turns being formed over the edges of the cylinder at the ends thereof.

Circuits in which the coils are connected may have leads which extend to usual terminal binding posts 5 mounted on the base plate 1.

This invention provides means for variably connecting the turns of the coils which are wound on the cylinders 3 with an external circuit and due to the provision of the improved form of coils and contacting or switching means embodied in the present invention, it is possible to effect the adjustments of these variable connections with a high degree of accuracy.

In each of the constructions shown, a shaft 6 is journaled in the uprights 2 and

projects outwardly from the ends of the cylinder. Said shafts 6 preferably are provided at the outer end with a suitable operating dial (not shown). Mounted on said shaft 6 either at one or both ends thereof is a switching or contact member 7 which frictionally engages the conductors 4 at the ends of the cylinder. Said conductors 4 are insulated from each other by the usual coating of insulating material and at the ends of the cylinder this material is preferably removed so that an electric circuit may be completed between each turn of the coil and the contact members 7 when the same are in engagement therewith. Said contact members 7 are preferably of such form as to engage but one conductor at any given time, and consequently, a very accurate adjustment of the coil relative to the circuit may be effected. Connected to the free end of each of said contact members 7 is a flexible conductor 8 which extends from the contact member to one of the binding or terminal posts 5.

In the constructions of Figures 4 to 7 inclusive is shown a plurality of coils superposed on the cylinder 3, the turns of each coil extending longitudinally of the cylinder and parallel to the axis thereof. These coils are preferably separated by layers of suitable insulating material such as shown at 9, 10 and 11 in Figure 5. The terminals of these coils are connected with the binding post 5 either directly or through contact members 7 as the conditions of the particular circuit may require. In this construction, adjustment of the outer coil relative to the circuit may be effected by means of a contact member 12 which is similar in construction to the contact members 7 and which is mounted on an insulated sleeve 13 rotatable on the shaft 6 and operable, if desired, through the medium of a suitable dial secured thereto (not shown). It will, of course, by understood that in the construction just described, the outermost coil does not entirely cover the inner coil, and because of this construction, it is possible to make contact with the ends of a portion of each coil.

In this construction, the contact member 7 which contacts the ends of the turns of the conductor 4 is insulated from the shaft 6, being mounted on an insulating tube 16 rotatable on said shaft and adjustable independently thereof.

In the constructions illustrated in Figures 9 and 10, a semi-cylinder 17 concentric with the cylinder 3 is mounted inside thereof on the shaft 6 and spaced therefrom. Wound on said semi-cylinder 17 is a coil 18, the turns of which extend parallel to the conductors 4 on the cylinder 3.

Terminal conductors 19 of the coils 4 and 18 lead to the usual binding posts 5 on the

base 1 and since the semi-cylinder 17 is rotatable inside the cylinder 3 by rotation of the shaft 6, a further variation of the inductance of the circuit may be obtained through such relative rotation. Further adjustment is provided for by means of a contact member 20 which is similar to the contact member 7 and which is mounted on an insulating sleeve 20, rotatably mounted on the shaft 6. Said contact member 20 is adapted to contact the ends of the turns of the coil formed by the conductor 4 in the manner previously described.

In Figures 11 and 12, we have illustrated a construction wherein a plurality of contact members similar to the contact member 7 may be separately moved into adjusting position relative to the ends of the turns formed by the conductor 4 to effect an exceedingly accurate adjustment of the concentrated inductance interposed in the circuit by said coil. In addition to the contact member 7 which is mounted on the shaft 6 at one end thereof, the coil is provided with additional contact members 22 and 23 which are separably rotatable on the shaft 6 and which are insulated from said shaft and from each other by insulating sleeves 24 and 25, respectively. It will, of course, be understood that each of said sleeves may be provided with an adjusting dial and that any well-known form of dials may be used.

It will be apparent from the foregoing description that this invention provides an improved concentrated impedance which may be conveniently used in an electric circuit and which may be varied to effect an exceedingly accurate adjustment. It will also be noted that with the construction provided it is possible to make separate contacts with each turn of the coil and when this apparatus is used as a coupler in a radio circuit, the accurate adjustments which may be attained by a sliding type coupled are closely approximated.

It will also be apparent that the form of apparatus shown in Figures 9 and 10 may be used as a variometer which is capable of very accurate adjustment.

In the form of apparatus shown in Figure 8, a concentrated impedance comprising inductance and capacity is provided in such a form that a minimum space is required and of such construction that the necessary adjustments may be conveniently made. The apparatus of this invention may be economically manufactured, is durable and, as previously pointed out, occupies a minimum of space.

We are aware that numerous details of construction may be varied through a wide range without departing from the principles of this invention, and we therefore do not purpose limiting the patent granted, otherwise than necessitated by the prior art.

We claim as our invention:

In a device of the class described, concentric spaced relatively rotatable hollow cylindrical members, a base, and a pair of supporting members secured to said base and extending upward therefrom at either end of said cylindrical members for supporting the same, a shaft, said shaft being supported by and extending through said supporting members, a conductor coiled on each of said members with the turns of each coil extend-

ing longitudinally on the inner and outer peripheries of the member on which it is wound, uninsulated portions at the ends of certain of said turns, and movable contacting means for contacting said uninsulated portions.

In witness whereof, we have hereunto subscribed our names.

DAVID A. NICOSIA.
HARRY SIPPEL.
